(57) CLAIM

The ornamental design for a wallet, as shown and described.

DESCRIPTION

FIG. 1 is a top plan view of a wallet showing our new design.

FIG. 2 is a front elevational view thereof.

FIG. 3 is a left side elevational view thereof.

FIG. 4 is a rear elevational view thereof.

FIG. 5 is a right side elevational view thereof.

FIG. 6 is a bottom plan view thereof.

FIG. 7 is a perspective view of the top, front and right sides thereof.

FIG. 8 is a perspective view of the inside of the wallet, showing a partition panel pivoted in the up position.

FIG. 9 is a perspective view of the inside of the wallet, showing the partition panel pivoted in the down position.

FIG. 10 is a perspective view of the inside of wallet, showing the top portion of the partition panel flipped open.

FIG. 11 is a perspective view of the inside of the wallet, show in the fully open position.

FIG. 12 is a perspective view of the inside of the wallet, shown with the top portion of the partition panel partially open; and, FIG. 13 is a perspective view of the inside of the wallet, shown with the partition panel partially in the up position.

The symbol and word "TRU VIRTU" forming part of the claimed design is a registered trademark of Thomas Wingerter and Katrin Mengel of GERMANY Schluterstr, 22 20146 Hamburg.
